UNITED STATES PATENT OFFICE.

PETER A. ALTMAIER, OF HARRISBURG, PENNSYLVANIA.

MAGAZINE FIRE-ARM.

SPECIFICATION forming part of Letters Patent No. 370,032, dated September 20, 1887.

Application filed April 8, 1887. Serial No. 234,174. (No model.)

To all whom it may concern:

Be it known that I, PETER A. ALTMAIER, of Harrisburg, in the county of Dauphin and State of Pennsylvania, have invented certain new and useful Improvements in Breech-Loading and Magazine Guns; and I do hereby declare the following to be a full, clear, and exact description of the same, reference being had to the accompanying drawings, forming a part of this specification, and to the figures and letters of reference marked thereon.

This invention relates to improvements in magazine-guns of the class shown in my Patent No. 343,883; and it consists in the novel and improved constructions, combinations, and arrangements of parts, as hereinafter fully described, and pointed out in the claims.

In the accompanying drawings, illustrating my invention, Figures 1 and 2 are side elevations of the breech-frame and operating mechanisms, the side plate being removed and the locking and feeding devices shown in different positions. Fig. 3 is a similar view partly in section, the carrier and breech-block being shown fully retracted and the cartridge-lifter elevated. Fig. 4 is a side elevation of the breech-frame. Fig. 5 is a view in perspective of the sliding carrier and its breech-block. Figs. 6 to 10, inclusive, represent detached parts of the feeding and locking mechanisms. Figs. 11 and 12 are side views of the gun, showing the plate covering the feeding-orifice. Figs. 13 and 14 are detail views of the covering-plate.

Similar letters of reference in the several figures indicate the same parts.

In illustrating the application of my present inventions I have shown them as applied to a gun having the general characteristics of that described in my prior patent, No. 343,883.

The letter A designates the breech-frame; B, the barrel; C, the reciprocating carrier; C', the breech-block; F, the hammer; f', the locking-hook; G' and D, the locking-levers; E, the hand-lever, and N the cartridge-lifter.

The carrier C, arranged to slide in ways beneath the barrel, is formed with a longitudinal perforation or opening to receive the cartridges and a vertical slot or opening, c, immediately in front of the breech-block, through which opening the cartridges are transferred by the lifter N and deposited or held in posi-

tion for insertion in the barrel. The front end, c', of the carrier is reduced, so as to fit within the rear end of the magazine-tube B', 55 and an opening or slot, S, is formed in the side of the carrier, through which the cartridges are inserted, as hereinafter explained.

The hand-lever E, pivotally supported at e' in the breech-frame, is provided with a shoulder, e, engaging the locking-lever D to lock and release the carrier.

Beneath the carrier C is detachably secured a plate, 1, whose forward end may be attached to the carrier, as by screw 2, passing through a lug, 3, while its rear end is supported between lugs 4 and on pin 5. This plate 1 is provided with a slot, 6, extending downward toward the rear, as shown more clearly in Fig. 7. The forward or shorter end of the hand-lever E 70 is bifurcated to receive this plate 1, and is provided with a pin, 7, passing through the slot 6. On one side of the plate 1 the end of the lever E is provided with a shoulder, 8, and notch 9, co-operating with the hooked end 10 of locking-lever G', while on the other side is formed a cam or toe, 11. Supported so as to oscillate on pin 5 is a link or lever, 12, for actuating the cartridge-lifter, the forward end, 13, of said lever being provided or formed with a curved 80 surface for co-operating with the lever E, as hereinafter described, while its rear end is furnished with a curved bearing, 14, upon which the lifter N rests, the latter being held in place by a pin, 15, passing through a slot 85 or opening, 16, in the lever. A pin, 17, on the side of the lever 12, co-operating with shoulders 18 and 19 on lug 4, serves to limit the throw of the lever, and a spring, 20, fastened at its rear end to the lever and provided with 90 an edge or shoulder, 21, co-operating with the oppositely-inclined faces of a cam or projection, 22, on lugs 4, serves to throw the lever up or down as the shoulder on the spring bears against either face of the cam 22.

It will be observed that the plate 1, lugs 4, and lever 12 are centrally located beneath the carrier, so as to reciprocate between the arms of the locking-lever D. The carrier N rests loosely upon the curved end of the lever 12, 100 and it is guided in its vertical movements by a rib, 23, co-operating with guides on the inner wall of slot c in the carrier C.

The devices described constitute the whole

of the feeding mechanism, and its action is as follows: When the gun is in condition to be fired, the parts remain as shown in Fig. 1—that is to say, the carrier C is at the extreme 5 of its forward movement, the breech-block is held against the barrel, the locking devices (of any approved form) are in position, the hand-lever is elevated and held against the stock, with the pin 7 in its forward end resting in the lower end of slot 6 in the plate 1, the lever 12 is held by the spring 20 in a position substantially parallel with the under side of the carrier, and the lifter N is depressed below the opening in the carrier and lies in 10 position to receive the rearmost cartridge. If, now, the hand-lever is depressed, the pin 7 will, as it is elevated, engage the rear wall of the slot 6 in plate 1, and, acting thereon, will move the carrier back until the toe 11 is 15 brought into contact with the inclined lower face of lever 12, when the pressure of the lever upon the carrier to force the latter back will be transferred from the pin 7 and plate 1 to the toe 11 and end 13 of lever 12. The forward motion of the hand-lever being continued, 20 the toe 11, as it vibrates upon the pivot, is carried above the end 13 of the lever 12, as shown in Fig. 2. Up to this time the forward, now upper, end of the hand-lever has been 25 approaching the carrier, and the pressure applied to the end of lever 12 to force back the carrier has been directed on a line above the pivotal point at which said lever is attached to the carrier; but as the forward, now upper, 30 end of the hand-lever begins to descend the line of direction is altered, and instead of forcing the carrier back the toe 11 will now press down upon the upper face of the end 13 of lever 12. The carrier and breech-block have now been re- 35 tracted sufficiently to uncover the slot c in the carrier, and as the hand-lever continues to move forward the pin 7 is moved down in slot 6, and the toe 11, now bearing upon the upper surface of lever 12, presses the forward end of 40 said lever down, thereby elevating the lifter N, and with it the cartridge, which latter is held in position in rear of the barrel until by the forward movement of the breech-block its forward end is thrust into the barrel. The lifter 45 N, together with the cartridge lying upon it, is held in this elevated position by the spring 20, whose end 21, having been carried across the point of cam 22 on lugs 4 by the tilting of lever 12, to which it is attached, now bears 50 upon the upper face of said cam 22. The cartridge having been thus elevated into position to be inserted within the barrel, the hand-lever is drawn backward to advance the breech-block and force the cartridge into the barrel. 55 As the forward, now upper, end of the hand-lever moves upward the toe 11 leaves the lever 12, and the pin 7, bearing against the front wall of slot 6, forces the carrier forward, the pin 7 first rising and then descending within 60 the slot 6. No movements of the carrier take place until the pin 7 has arrived at or near

the upper end of slot 6, and during this interval the lifter N remains elevated.

The lifter N is grooved longitudinally on its upper surface to retain and hold the cartridge 70 centrally in line with the bore of the barrel, and its front end is slightly curved downward, as shown. A slot or recess, 30, is formed under the rear end of the barrel (when, as in the present instance, the barrel is provided with 75 a square or flat base resting above the carrier) to receive or accommodate the front end of the lifter; or, if preferred, the front end of the lifter may be cut away, as in my said prior patent, the purpose and object of this arrangement being to permit a limited forward movement of the carrier to insert the cartridge 80 while the lifter remains in its elevated position. Thus, when the pin 7 takes a bearing against the front wall of the slot 6, near the 85 upper end thereof, the carrier will be advanced, the lifter being retained in position by the spring 20 until the end 13 of lever 12 is brought into contact with the hand-lever E at a point between the pivot and toe 11. This action 90 takes place at or about the time the pin 7 begins descending the slot 6, at which time the movement of the carrier is more rapid than the descent of the forward end of the hand-lever, since, as the latter is carried forward and downward, the end 13 of the lever 12 is drawn over and forced upward by the curved surface 31 of the hand-lever. In this way a quick but positive movement is given to the lever 12 for effecting the withdrawal of the lifter from 95 between the barrel and breech-block as the latter is advanced. This action of the hand-lever 100 upon the lever 12 continues until the end of the spring 20 is carried beyond the apex of cam 22, and as soon as this takes place the pressure of 105 the spring upon the lower surface of the cam 22 forces the forward end of the lever 12 up to the position shown in Fig. 1, thereby completely withdrawing the lifter. It will be observed that the spring 20 is thus made to supplement the 110 action of the hand-lever upon the lifter in both directions, for as soon as the spring is carried beyond the apex of the cam 22 in either direction it acts instantly to propel the lever 12, to which it is attached. Said spring serves also 115 to retain the lever 12 in position, up or down, when not acted upon by the hand-lever. Thus it will be seen the entire cartridge-feeding mechanism is composed of but four pieces—the plate 1, lever 12, spring 20, and lifter N— 120 co-operating with the hand-lever and carrier, as described.

The locking devices shown for holding and releasing the carrier are similar in construction and operation to those described in my 125 prior patent, with the exception of the locking-lever G', whose rear end is formed with a hook, 10, whose point co-operates with a hook or shoulder, 8, on the hand-lever, instead of with its rounded end, as in my prior patent, 130 the reversed inclines on the hooks 10 and 8 serving, when the hand-lever is first depressed,

to raise the rear and depress the front end of said locking-lever G' much quicker, and thereby unlock the carrier with but a slight movement of the hand-lever.

5 The cartridges are inserted or fed into the magazine through a slot or opening, S, in the side of the carrier, Figs. 3 and 5, and a corresponding slot or opening, 41, in the side of the breech-frame. At or near the forward end of 10 the slot 41 is secured a spring or spring-pressed plate, 42. This plate 42 extends back and covers a portion only of the slot 41, sufficient space being left for the ready insertion of the end of a cartridge, and to facilitate this 15 operation the rear or free end of the opening is bent or curved outward, while the inner face, or that next the carrier, serves, when the plate is pressed inward, to partially close the slot 40 in the carrier and direct the cartridge or 20 cartridges therein onto the lifter N. Over the slot 41 is fitted a plate, 44, pivotally attached to the breech-frame at 45, and provided with a projecting plate or rib, 46, fitting, when down, between undercut guides 47, and said 25 rib 46 also engages the spring 42 to press and hold the latter inward. The pivot 45, upon which this plate 44 is mounted, extends through the breech-frame and carries on its inner end a cam or lever, 48, projected within a slot or 30 groove, 49, formed in the side of the carrier, so that when the carrier is retracted the front wall or equivalent portion of the slot 49, by striking against said cam or lever 48, will force the plate 44 down and into position to cover 35 the feeding-opening in the side of the breech-frame. By this means not only is the closing of the plate insured when the carrier is retracted, but the pin 45 serves as a stop for limiting the rearward movement of the carrier. 40

At the rear end of the lifter N is formed a notch or shoulder, 50, to receive and accommodate the flange of the cartridge, and on the opposite sides of the face of the 45 breech-block are formed vertical guides 51 to receive and guide the flanged head of the cartridge, and thus prevent it from tilting or turning laterally while being elevated. In the face of the breech-block is formed a recess, 52, for the reception of a pivoted presser, 54, provided with an opening for the firing-pin 55, between which and the said presser 54 is interposed the spring 56. On top of the breech-block is secured a spring, 57, whose 50 front end overhangs the face of the breech-block and is provided with a catch, 58. The action of these parts is as follows: When the breech-block is closed and the lifter down, the rear cartridge in the magazine or carrier will 55 be forced backward over the lifter until the flange at the head falls into the recess or below the end of the lifter. The hand-lever being now operated to retract the carrier, as soon as the toe 11 engages and forces down 60 the lever 12 the lifter is elevated, carrying the cartridge up in front of the breech-block. As the cartridge emerges from within the

carrier it is supported by the guides 51, which engage the flange of the head at the sides at the same time the presser 54 is forced back 70 into the recess in the face of the breech-block. The guiding-flanges 51 expand or widen near the top, so that as the cartridge is brought into position in front of the barrel its flanged head will pass from under the guides 51 and 75 enter behind the hook or catch 58. The cartridge is now supported against the face of the breech-block and in line with the base of the barrel by the lifter N and the catch 58 of the extractor, the presser 54 operating against 80 the head to hold the flange of the cartridge pressed against the end of the lifter and the bullet elevated to the level of the bore.

As before remarked, in drawing the hand-lever back the carrier is advanced slightly 85 before the lifter begins to descend, so that the cartridge will be securely held until the front end has been inserted in the barrel, and when this has been done and the lifter descends the rear end of the cartridge is supported and 90 prevented from falling by the presser acting against the head in a direction tending to tilt the cartridge upward.

The extractor 58 retains its hold on the flange of the cartridge while the latter remains in the barrel and after the breech-block has been closed, so that when the carrier is retracted the shell or cartridge will at the same time be withdrawn by the extractor 58, and will be removed or thrown off by the presser 100 54, which latter acts against the head of the shell in a direction to tilt it upward, and thus withdraw it from under the extractor.

Although the presser co-operating with the extractor as described may be employed for 105 ejecting the shells, other more prompt and effective means are provided, consisting of the vertically-moving lifter N, which latter, as its spring 20 passes the apex of cam 22, is thrown suddenly upward, and the cartridge carried 110 by the lifter, or the lifter itself striking the shell, throws the latter out entirely clear of the gun.

As will readily be understood, the gun can be used either as a magazine or a breech 115 loader, and when employed as a breech-loader alone the cartridges can be inserted either through the opening in the side of the breech-frame or directly in the barrel.

If while the magazine is charged it should 120 be desired to load direct without drawing upon the magazine, by turning the plate 44 up, and thereby advancing the point of the arm or cam 48, the rearward movement of the carrier can be arrested just before the toe 11 of the 125 hand-lever operates to depress the end 13 of lever 12, at which time the breech-block will have been retracted sufficiently to permit of the withdrawal or insertion of a cartridge, while the lifter N and the cartridge lying upon it will remain down in position to be elevated and inserted whenever the carrier is pressed back beyond the point indicated, which can be done, even when plate 44 is elevated, by the

application of sufficient power to the hand-lever to force the said plate 44 down, as before described.

Among the numerous and by no means least important advantages and benefits secured by the construction shown and described may be mentioned the simplicity and durability of the working mechanism, the relatively small number of parts employed, and their arrangement and combination in a manner tending to reduce to the minimum all liability of breakage, cramping, or any other derangement of the parts such as would interfere with or prevent their proper action.

Having thus described my invention, what I claim as new is—

1. The combination, with the barrel, reciprocating carrier, and the hand-lever connected to the carrier to reciprocate the latter, of the lever pivoted on the carrier, the lifter loosely supported upon said lever, and a spring-and-cam connection between said lever and the carrier adapted to supplement the action of the hand-lever on the lifter, substantially as described.

2. The combination, with the barrel, the carrier, and breech-block supported and arranged to slide in ways beneath the barrel, of the hand-lever pivoted in the barrel-frame, the plate secured rigidly to the under side of the carrier, having the rearwardly-inclined slot, and the pin carried by the hand-lever co-operating with the slot in the plate to slide the carrier when the hand-lever is moved on its pivot, substantially as described.

3. In combination with the breech-frame, the barrel, and a reciprocating carrier provided with a breech-block, the slotted plate secured to the carrier, the lever carrying the lifter pivoted upon the carrier, and the hand-lever pivoted in the breech-frame, the end of said hand-lever being provided with a pin working in the slotted plate, and a toe or projection for engaging the lever carrying the lifter, substantially as described.

4. In combination with the breech-frame, barrel, reciprocating carrier, and breech-block, the bifurcated locking-lever D, the slotted plate 1, secured beneath the carrier, the lever 12, carrying the lifter N and spring 20, whose free end engages the cam 22 on the carrier, and the hand-lever pivoted in the breech-frame below the carrier and provided with a pin for engaging the slotted plate, and a toe or projection for co-operating with the lever 12, substantially as and for the purpose set forth.

5. In a gun such as described, the combination, with the breech-frame, barrel, and longitudinally-perforated carrier, of the lifter N, supported loosely upon a lever, 12, pivoted beneath the carrier, a hand-lever co-operating with said lever 12 to oscillate the latter, and thus reciprocate the lifter, and a spring, 20, engaging a cam, 22, forming a connection between the lever and the carrier and operating to propel the lifter at or near the end of its stroke, substantially as described.

6. In combination with the breech-frame, barrel, carrier, and breech-block, the slotted plate 1, secured beneath the carrier, the lever 12, pivotally supported between lugs on the carrier and provided with a spring, 20, whose free end bears against cam 22 on said lugs, and a lifter, N, loosely connected to said lever 12, substantially as described.

7. In a gun such as described, and as a means for elevating the cartridge and presenting the latter in line with the bore of the barrel, the combination, with the barrel, of the lifter N, recessed on its under surface and fitted to the curved end of a pivoted lever, 12, the spring 20, carried by said lever and arranged to engage a double-faced cam or projection, 22, on the carrier, and a lever adapted to engage and force said lever 12 in opposite directions alternately to elevate or depress the lifter, and in so doing to cause the spring 20 to pass the apex of the cam 22 and throw the lever up or down, substantially as described.

8. In combination with the breech-frame, barrel, reciprocating carrier, and its breech-block, and the cartridge-lifter working in guides in the carrier and supported upon a lever, 12, pivoted beneath the carrier, the slotted plate 1, secured to the carrier, the locking-levers G' and D, supported in the breech-frame and engaging the carrier, and the hand-lever pivoted in the breech-frame and provided with a pin co-operating with slotted plate 1, and projections engaging the locking-levers G' and D, and the lever 12, carrying the lifter, substantially as and for the purpose described.

9. In combination with the reciprocating carrier and its breech-block, the lifter N, guided vertically through a slot in said carrier, the extractor mounted upon the breech-block, a lever, 12, actuated by the hand-lever to elevate and depress the lifter, and a spring co-operating with said lever 12 to supplement the action of the hand-lever toward the end of the movement of the lever 12, substantially as and for the purpose set forth.

10. In a gun such as described, having a reciprocating carrier with a side opening for the insertion of cartridges, and in combination with said carrier and the breech-frame, also provided with an opening such as described above, the spring-plate fastened to the breech-frame and occupying the front portion of the opening therein, the rear end of said spring being bent or curved outward, substantially as and for the purpose set forth.

11. In combination with the breech-frame and reciprocating carrier, each provided with a slot or opening in the side for the insertion of cartridges within the carrier, the spring-plate and pivoted outer plate secured to the breech-frame, the latter formed with an incline adapted to press the former inward when closed, substantially as described.

12. In combination with the breech-frame and reciprocating carrier, each provided with an opening such as described for the insertion of cartridges, a cover or plate for the

opening in the breech-frame, said cover or plate being connected to an arm or cam in line with a projection on the carrier, whereby as the carrier is retracted said arm will be engaged to arrest the movement of the carrier or close the cover down over the feed-orifice, substantially as set forth.

13. In combination with the breech-frame and reciprocating carrier, both provided with an orifice or slot in the side to permit the insertion of cartridges, the cover or plate pivoted on the outside of the breech-frame, and with an arm or cam attached to the pivot, said arm or cam co-operating with a shoulder 15 or the wall of a recess in the carrier, as and for the purpose set forth.

14. In combination with the reciprocating carrier and the breech-frame, both provided with a slot or opening for the admission of cartridges, the spring-plate 42, and the pivoted outer plate, 44, provided with a rib, 46, fitted to engage guides on the breech-frame, substantially as described.

15. In combination with the breech-frame

and a carrier reciprocating therein, each provided with a slot or opening in the side, as described, the pivot 45, passing through the side of the breech-frame and connected at one end to a plate or cover, 44, and at the other to a cam or lever, 48, the latter so arranged as 30 to be engaged by the front wall of a slot in the side of the carrier when the plate 44 is elevated, and operating to depress or close the latter, substantially as described.

16. In a gun such as described, and in combination with the barrel, breech-frame, and reciprocating breech-block provided with the extractor and spring-operated presser, the vertically-reciprocating lifter N, a lever for actuating said lifter, and a spring operating to 40 throw the lifter quickly upward to eject the shell when withdrawn by the extractor, substantially as described.

PETER A. ALTMAIER.
